HINGED EXPANSION JOINT

Filed Oct. 19, 1925

A. C. Fischer

Inventor:

UNITED STATES PATENT OFFICE.

ALBERT C. FISCHER, OF CHICAGO, ILLINOIS.

HINGED EXPANSION JOINT.

Application filed October 10, 1925. Serial No. 28,895.

This invention relates to an improvement in joining together sections of expansion joint so that when they are placed in the roadway the ends which abut against each other will be held firmly in place while the concrete is poured against them. This has been accomplished in the past by means of staples driven on either side of the edges to be united at the time of making installation or by cementing a piece of fabric or saturated felt at the junction point of the two pieces, then folding the pieces over upon each other and preparing for shipment. These strips are then taken out of the crates, placed against a backing board which is devised to support the expansion joint in place, and the two strips of joint are supported and held together by the fabric and cemented across the edges thereof, holding the two pieces together. This involves considerable work, and the fabric may readily be torn apart and the staples being of light construction are subject to bending out of shape.

My invention relates to the use of a longer and stronger staple and driving the staples into the abutting pieces of expansion joint at their edges rather than at their sides, the prongs of the staples being driven at equal distances from the dividing point into the adjacent slabs of expansion joint in the upper and lower edges thereof centrally located. It will be found that these pieces of expansion joint can be folded over upon each other and when again straightened out the hinge action will be such that the abutting edges will fit closely together.

My invention is further described by referring to Figure 1 which represents a strong rounded staple adapted to permit a hinge action without disturbing to any degree the mastic surrounding it.

Figure 2 represents two sections of expansion joint held together at their butt ends with two staples driven in the upper and lower edges thereof.

Figure 3 illustrates two slabs of expansion joint having their edges adjacent to each other with a hinging staple driven centrally

therein, the prongs equal distances from the edges of the respective division line of the two slabs, said staple being so formed and of a sufficient size for the respective thicknesses of joint so that the prongs will be embedded, sufficiently removed from the edge to permit the expansion joint to pivot upon the prong. In this figure (a) represents the body structure of the respective slabs of joint, (b) the joining section of the prongs and (c) the respective prongs. In order to function properly, it is necessary that the prong (c) in one section of joint has sufficient distance from the edge to permit the joint to pivot. This is also true of the opposite section.

Figure 4 shows the two slabs of expansion joint in process of pivoting or hinging, in which (aa) represents the expansion joint, (b) the crowning section of the staple.

Figure 5 illustrates the two pieces of expansion joint after they have been placed one above the other for shipment, (cc) representing the expansion material and (b) the staple in the edges of said expansion material.

Figure 6 illustrates the same double unit of expansion joint opened out ready for use, in which (aa) represents the expansion joint sections and (b) the head of the staple driven in one edge thereof.

This hinged expansion joint may be prepared at the factory or the method employed, and the staples and expansion joint shipped to the work and the staples inserted at the time of laying up the expansion joint.

I claim:

An expansion joint comprising sections of preformed strips of compressible material joined with their ends in confronting and abutting relation by staples, said staples being imbedded in the crown and base of the sections, the prongs thereof bridging the ends of the sections substantially as and for the purpose described.

In testimony whereof I have signed my name to this specification on this 8th day of October, A. D., 1925.

ALBERT C. FISCHER.
